UNITED STATES PATENT OFFICE

1,998,574

SQUARE

Carl E. Faust, Chicago, Ill.

Application October 7, 1931, Serial No. 567,459

6 Claims. (Cl. 33—115)

This invention relates generally to squares of the type used by carpenters and other craftsmen, and more particularly to a folding device.

It is the general object of the invention to provide a new and improved square of simple construction and capable of having one leg thereof folded with respect to the other when not in use.

Other objects are to provide a folding square comprising two pivotally connected members one of which is provided with a recess for receiving the other when the parts are folded together; to provide such a square embodying a pocket for holding a scratch-awl and so arranged that the awl cannot fall out when the square is folded; and to provide an improved device of this character equipped with leveling tubes.

Further objects and advantages will become apparent from the following detailed description taken in connection with the accompanying drawing, in which:

Fig. 1 is a plan view of a preferred form of the invention.

Fig. 1^a is an end view.

Fig. 2 is a similar view showing the parts folded together.

Fig. 3 is an edge view along the line 3—3 of Fig. 1.

Fig. 4 is a plan view illustrating another form of the invention.

Fig. 4^a is a section along the line 4^a—4^a of Fig. 4.

Fig. 5 is a fragmentary plan view of still another form of the invention.

Fig. 6 is a section along the line 6—6 of Fig. 5.

Fig. 7 is a section along the line 7—7 of Fig. 5.

For purposes of disclosure I have illustrated in the drawing and shall hereinafter describe in detail several different embodiments of the invention, but it is to be understood that I do not thereby intend to limit the invention to the specific forms disclosed but aim to cover all modifications and alternative constructions falling within the spirit and scope of the invention as expressed in the appended claims.

As illustrated in the drawing, the invention comprises generally a pair of members arranged to form the two legs of a square, one having a recess therein into which the other part may be folded, and means for pivoting the members together on an axis substantially bisecting the angle between the legs of the square. Thus, as illustrated in Figs. 1 and 2, a substantially rectangular member 10 is arranged to form one leg of the device, and a second member 11 has a thinner blade or leg portion 12 and a connecting portion

13 extending from one end thereof. The member 11 is pivotally connected to the member 10 by means of a diagonally positioned pin 14 which extends through the member 10 at an angle of 45° with respect to the side edges of said member and passes through the connecting portion 13 of the member 11. Thus one member may be swung from the open operative position, as shown in Fig. 1, to a closed or folded position, as illustrated in Fig. 2.

In the form illustrated in Figs. 1 and 2 the end of the connecting portion 13 is circular in shape and the member 10 is provided with an irregularly shaped aperture or recess 15 arranged to receive the entire member 11, as illustrated in Fig. 2, said recess having a transversely extending slot portion 16 into which the connecting portion 13 fits when the square is open. It will be readily apparent that by so forming the parts and connecting them together they may be folded to a convenient form when not in use. Furthermore shoulders 16 formed on the member 11 fit against the adjacent edge portion 17 of the member 10 when the device is open, and cooperate with the pivot pin 14 to secure the parts accurately at right angles to each other. Preferably a rib 18 is secured to or formed on the member 10 on the under side and along the inner edge thereof. This rib serves as a guide during the use of the square and also limits the pivotal movement of the member 11.

A pocket 20 may be formed in the end of the member 11 for receiving a scratch-awl 21. As illustrated herein this pocket has a wide end portion for receiving the head of the awl and is so positioned that when the parts are folded together as illustrated in Fig. 2 the end portion 22 of the member 10 serves as a means for retaining the awl in the pocket. In addition leveling or bubble tubes 23 and 24 may be provided on the side and end of the member 10 so as to enable the device to be used for leveling purposes.

In the form illustrated in Fig. 4, a member 10' is provided with a recess 15' for receiving a pivoted member 11'. In this form, however, a connecting portion 13' on the end of the member 11' is in the form of an arcuately shaped arm, a pivot pin 14 extending through both members so as to pivot them together on a 45° axis. Preferably, yieldable detent means is provided for securing the parts in their open and folded positions. As illustrated herein this means is in the form of a pair of spring pressed balls 25 positioned in recesses 26 which are partly closed at their lower ends 27 so as to permit the balls 25

to project out a limited distance. The arcuate connecting portion 13' is provided with shallow recesses 28 in which the balls engage. It will be evident that whether one detent device is provided or two the parts will be effectively held in both their open and closed positions. The leg portion of the member 11' is preferably thinner than the member 10' so as to facilitate the use of the device.

10 As illustrated in Fig. 4, leveling tubes 23' and 24' are shown positioned along the side and end of the rectangular portion of the aperture 15'. By so positioning the tubes they are effectively protected when the square is folded.

15 In the form illustrated in Figs. 5 to 7, a member 10'' forming one leg of the square is substantially thicker than the corresponding members illustrated in Figs. 1 to 4, and a recess 15'' is provided which extends approximately two-thirds 20 of the way through the member. This recess has a circular portion 30 formed with a spherical bottom and arranged to receive a ball 31 on the connecting portion 13'' of a second leg member 11''. In order to provide the necessary clearance 25 for the member 11'' during its swinging movement, a portion of the member 10'' is cut away at 33. In this form of the invention the recess 15'' extends all the way to the right-hand end 30 of the member 10'', as shown in Fig. 6. Preferably a semicircular groove 32 is provided in the member 10'' so as to facilitate grasping the end 35 of the member 11'' when in its folded position.

I claim as my invention:

1. A square comprising, in combination, a pair 35 of members forming the legs thereof, means connecting said members pivotally together on a 45° angle so that they may be moved relatively to each other from a folded parallel position to an open right angle operative position, one of 40 said members having a recess therein arranged to receive the other member when in its folded position, and having a transversely extending slot arranged to receive a portion of said other member when in its open position.

45 2. A square comprising, in combination, two members forming the legs thereof, one of said members having an irregular aperture therein comprising a circular recess adjacent one end, a slot extending transversely between said recess 50 and the edge of the member and a slot extending longitudinally away from said recess, the other member comprising a circular portion arranged to fit in said recess, a narrow neck portion arranged to fit in one of said slots, and a wider 55 blade portion, a pivot pin extending diametrically

through said recess and through the circular portion of said one member, and a rib extending along one edge of said member across said transverse slot.

3. A square comprising, in combination, a first substantially rectangular member forming one leg, a second member forming the other leg and having a connecting portion extending from one end thereof, said first member having a recess therein into which said second member fits so that the parts may be folded together and into part of which the connecting portion fits when the parts are opened, means pivoting said second member to said first member for swinging movement on an axis positioned 45° with respect to the first member, and yieldable means for engaging and securing said second member in its open operative position.

4. A square comprising, in combination, a first substantially rectangular member forming one leg, a second member forming the other leg and having a connecting portion extending from one end thereof, said first member having a recess therein into which said second member and its connecting portion fits so that the parts may be folded together and also having a recess into which said connecting portion fits when the parts are swung open with respect to each other, means pivoting said second member to said first member for swinging movement on an axis positioned 45° with respect to the first member, and means for engaging and securing said second member in its open operative position.

5. A square comprising, in combination, two members forming the legs thereof, one member having a recess arranged to receive the other so that they may be folded together, the one surrounding the other, and means pivotally connecting said members together on a 45° axis so that when open the members form a right angle square.

6. A square comprising, in combination, a substantially rectangular member forming one leg thereof, a second member forming the other leg and having an arcuate portion extending from one end, said first member having a recess therein arranged to receive said second member, and a pivot pin extending through said first member and the arcuate portion of said second member at an angle of 45° to said first member so that the second member may be swung from a 90° open operative position to a folded position in said recess.

CARL E. FAUST.
